Primary Examiner — Jack Reickel*Assistant Examiner* — Sydney M Evans(74) *Attorney, Agent, or Firm* — Eric B. Fugett; Mark A. Pitchford; Pitchford Fugett, PLLC(57) **CLAIM**

The ornamental design for a storage panel connector as shown and described.

DESCRIPTION

FIG. 1 is a front perspective view of a storage panel connector showing our new design;

FIG. 2 is a back perspective view thereof;

FIG. 3 is a front view thereof;

FIG. 4 is a back view thereof;

FIG. 5 is a right side view thereof;

FIG. 6 is a left side view thereof;

FIG. 7 is a top view thereof; and,

FIG. 8 is a bottom view thereof.

The figures illustrate a storage panel connector.

Features of the article that are not shown are disclaimed.

1 Claim, 7 Drawing Sheets(56)
